UNITED STATES PATENT OFFICE.

JAMES V. REED, OF YONKERS, NEW YORK.

DESIGN FOR A SHAVING-CUP.

SPECIFICATION forming part of Design No. 34,709, dated July 2, 1901.

Application filed February 2, 1901. Serial No. 45,787. Term of patent 14 years.

To all whom it may concern:

Be it known that I, JAMES V. REED, a citizen of the United States, and a resident of Yonkers, in the county of Westchester and State of New York, have invented and produced a new and original Design for a Shaving-Cup, of which the following is a specification, reference being had to the accompanying drawings, forming part thereof.

Figure 1 is a plan view of a shaving-cup of my new design. Fig. 2 is a view in side elevation of the same.

As shown in the drawings, the leading or material feature of my design consists in the cup having a distinct body part and an elongated base portion *a* less in height than the

main body *b* of the cup and having in the upper edge of this extension as an essential feature a distinct depression *c* in the opposite edges.

The general outline of the structure as seen in side elevation is that of a rude sock with the toe portion slightly upturned.

Having described my invention, what I claim as new, and desire to secure by Letters Patent, is—

The design for a shaving-cup as herein shown and described.

JAMES V. REED.
